United States Patent Office

Des. 192,858
Patented May 22, 1962

192,858

KNIFE

Anton Jainecker, Pottenstein an der Trist, Austria, assignor to Vereinigte Metallwerke Ranshofen-Berndorf Aktiengesellschaft, Braunau (Inn), Austria, a corporation of Austria

Filed Apr. 21, 1959, Ser. No. 55,596

Term of patent 14 years

Claims priority, application Switzerland Feb. 19, 1959

(Cl. D22—3)

FIG.1

FIG.5

FIG. 1 is a side-elevational view of a knife embodying my new design;

FIG. 2 is a front-elevational view of the knife; and

FIGS. 3, 4 and 5 are cross-sectional views taken respectively along lines 3—3, 4—4 and 5—5 of FIG. 2.

I claim:

The ornamental design for a knife, as shown.
